UNITED STATES PATENT OFFICE.

ANNA HEUSER, OF PATERSON, NEW JERSEY.

DESIGN FOR CLOSED DRAWERS.

47,423.

Specification for Design.

Patented June 8, 1915.

Application filed September 10, 1914. Serial No. 861,154. Term of patent 14 years.

To all whom it may concern:

Be it known that I, ANNA HEUSER, a citizen of the United States, and a resident of Paterson, in the county of Passaic and State of New Jersey, have invented a new, original, and ornamental Design for Closed Drawers, of which the following is a specification, reference being had to the accompanying drawings, forming part thereof.

Figure 1 is a front elevation; and Fig. 2

is a perspective view of a pair of closed drawers showing my new design.

I claim:

The ornamental design for closed drawers, as shown.

ANNA HEUSER.
